TYPOGRAPHICAL COMPOSING AND
CASTING MACHINE

Richard Henry Scott, Enfield, and William Fairall Gorse and Arthur Staniland Hayward, Altrincham, England, assignors to Linotype and Machinery Limited, London, England, a limited liability company

Application November 23, 1940, Serial No. 366,810
In Great Britain December 6, 1939

24 Claims. (Cl. 199—49)

This invention relates to typographical composing and casting machines such as are known commercially under the registered trade-mark "Linotype" wherein circulating matrices are released from a magazine by a keyboard mechanism in the order in which their characters are to appear in print and then composed in line in an assembling elevator, the composed line transferred to a line transporter or so-called first elevator which descends to present the said line to the face of a mold, the mold filled with molten metal to form a slug or cast type bar against the matrices which produce the type characters thereon and the matrices thereafter returned to the magazine from which they started.

In such machines the matrices are received by the jaw of the transporter at its line receiving position and in its normal cycle the transporter first moves from this position downwards to the line casting position, then upwards above the line receiving position to the matrix distributing position when it again descends to the line receiving position.

It is sometimes desirable that means shall be provided whereby the cycle of the transporter is varied such, for instance, as where it is proposed to introduce one or more hand composed lines from a font of matrices not at the time carried in the machine or from matrices which are too large or otherwise not intended for machine composition.

According to the present invention a typographical composing machine of the kind referred to is provided having a transporter cam and a transporter cam roller and selective mechanism for varying the cycle of the transporter so that the transporter jaws are raised and lowered between the line receiving and casting positions only when desired. The cycle of the transporter may be varied from that normally employed when matrices are being automatically composed by the use of the keyboard in such a manner that the transporter jaws are raised and lowered between the line receiving and casting positions only. Preferably, a double track is provided on the transporter cam and selective means are provided whereby the cam roller on the transporter lever is caused to pass over one track when the normal cycle is required and over the other when the cycle is required to be varied in manner aforesaid. The cam track may be provided with a raised portion having alternative tracks upon and below the same. Preferably, spring fingers are provided at either end thereof which are so disposed that the cam roller passes over the

same when the transporter is required to perform its normal cycle.

The said selective means may comprise an interponent adapted to cause one of said fingers 5 to be raised so that the cam roller is free to take the lower track, the said interponent being brought into operation when it is desired to change the transporter to the shorter cycle. The arrangement may be such that the interponent 10 is held out of engagement when the machine clutch is disengaged. Means may further be provided, operative when the mechanism is set for the shorter cycle, for carrying out any function normally performed by the transporter 15 when it rises to the line distribution position, such, for example, as the release of the space-band shifter carriage catch. A connection to release the said catch may be provided which is engaged by the transporter jaw at the line receiving position. The selecting mechanism may 20 be operated by hand or from some part of the machine. In one embodiment the said mechanism is actuated by the movement of the transporter head for example by rotation thereof.

In order that the invention may be more clearly understood a preferred embodiment thereof will now be described in detail with reference to the accompanying drawings in which:

Figure 1 is a section through a part of a typographical composing machine constructed according to the invention showing the transporter and the transporter cam;

Figures 2 and 3 are views of part of Figure 1 in the direction of the arrows X and Y respectively;

Figure 4 is a view of the upper part of the transporter viewed from the front of the machine;

Figure 5 is a view of the transporter cam in a different position to that of Figure 1 showing the operation of the interponent.

Figure 6 is a plan view of the selecting mechanism the subject of the invention;

Figure 7 is a view in the direction of the arrow in Figure 6;

Figure 8 is a side view of the transporter showing a modification of the invention, and

Figures 9 and 10 are similar views to Figures 4 and 6 showing the modification of Figure 8.

Referring to the drawings and first to Figures 1 to 7, the transporter 1 is raised and lowered in the normal way by engagement with a lever or system of levers 2 to the other end of which is secured a cam roller 3 which runs on a track 55 on the transporter cam 4. The transporter cam

according to the invention is formed with a double track, one track 5 following the normal configuration of the cam and having portions thereof so shaped that the cycle of movement of the transporter extends from the line receiving position to the casting position, thence upwards to the line distributing position and down again to the line receiving position. A second or alternative track 6 runs beneath that raised portion of the cam 5 which controls the uppermost movements of the transporter 1. At either end of the raised portion of the cam is located a pivoted finger and both of these fingers 7, 8 are normally held by means of tension springs 9, 10, in such a position that they form part of the upper cam track and constitute the portion of that track leading up to and from the highest portion thereof. The leading finger 7 is provided with an extension 11 upon which is mounted a pawl roller 12. The arrangement of the pawl roller 12 upon the finger 7 is such that pressure upon the said roller 12 causes the finger 7 to pivot, thereby leaving open a passage to the cam roller 3 along the lower track 6 of the transporter cam 4. The cam roller 3 knocks the finger 8 at the other end of the lower cam track 6 out of the way and the finger 8 springs back into position after the roller 3 has passed.

An interponent 13 is provided which is brought into such a position that it will engage the pawl roller 12 and raise the finger 7 when it is desired that the lower cam track 6 shall be traversed by the transporter cam roller 3 so that the cycle is varied from the normal. The said interponent 13 is disposed at the end of a rod 14 under the action of a tension spring 15 anchored to a fixed part of the machine 16, and tending to pull the interponent 13 into the path of the pawl roller 12. This spring 15 is normally not permitted to operate in this manner on account of a stop 17 on the said rod 14 against which a trip catch 18 is engaged. The said catch 18 is engaged at one end by a Bowden wire 19, pull on which causes the catch 18 to be held clear of the said stop 17 so that the interponent 13 is brought into operation by means of the spring 15 above referred to. The catch 18 is in the form of a bar and is pivoted at or about its centre 20 to a fixed part of the machine the other end 21 being also attached to a fixed point by means of a tension spring 22 so that the catch 18 tends normally to drop in behind the stop 17 on the rod 14 and hold the interponent 13 out of operation.

The end of the rod 14 which does not carry the interponent is engaged with one arm of a lever 23 the other arm 24 of which is engaged in the clutch mechanism and is rocked when the clutch is disengaged so that the lever moves about its pivot 25 and the trip catch 18 drops in behind the stop 17 on the rod 14 unless prevented by operation of the pull handle 26 of the Bowden wire. As the clutch 27 is disengaged at the end of a normal cycle when the transporter 1 is at the line receiving position the cam interponent 13 is normally held out of operation at this point.

As previously herein mentioned the construction herein described is particularly applicable for use where a hand composed line is to be inserted into the machine. In one form of apparatus providing for such use of hand composed tools, the transporter head 28 may be rotatable and provided with two elevator jaws one adapted for automatic machine composition 29 and the other detachable and preferably in the form of a

hand composing stick in which the matrix line is manually composed 30. The hand stick may then be inserted into the transporter head 28 which is then rotated so that the line therein is brought into position. It would be at this stage, when using the apparatus just mentioned, that the control 26 would be actuated and the interponent 13 brought into operation so that the transporter cycle is varied whereby the same only descends from the line receiving position to the casting position and back again.

In this arrangement an extension 31 may be provided on the detachable transporter jaw or hand stick 30 which is adapted to engage with a vertical push rod 32 secured in brackets 33 in the machine. The upper end of the push rod 31 is located adjacent to the catch 34 which normally holds the spaceband shifter carriage and which is usually released by the transporter jaw 35 so that the spaceband shifter carriage can move to the right for removal of the spacebands. In this case as the transporter jaw 35 does not ascend above the line receiving position the catch 34 is released by means of the push rod 32 which is actuated by means of the extension 31 in manner aforesaid. Where a special transporter head 28 such as is last referred to is not provided as a part of the machine, a catch may be provided on the transporter jaw to engage the push rod. The said catch may be manually or automatically movable into an inoperative position when the transporter is required to perform its normal cycle in which it rises to the line distributing position.

In the arrangement shown in Figures 8 and 9 on the rotation of the transporter head to bring the jaw 30 into the operative position automatically actuates the selecting mechanism and brings the interponent 13 into operation to vary the transporter cycle. In these figures the shaft 36 is carried in bearings in the transporter 1 and its upper end projects through the spindle 37 in the rotatable head 28. The said shaft 36 is fixed by means of a taper pin 38 to the brackets 39. The shaft 36 is provided with an eccentric body for a portion of its length carrying the full strokes of the transporter past a fixed point as best shown in Figure 8. A roller 40 which is carried by one end of a lever 41, is held in contact with the eccentric body portion of the shaft 36 by means of a spring 42 and the other end of the lever 41 engages lever 43 which is connected by means of the cable 19 to the catch 18. The lever 41 is carried on the vise frame and the lever 43 on a bracket mounted on the machine frame. The arrangement of these two levers is such that the vise may be opened without interference and they are also so disposed that the selecting mechanism may be operated by hand by means of the lever 43 when an ordinary transporter head is employed and the operator desires to repeat the casting cycle.

In Figure 10 the catch 18 is shown holding the selecting mechanism inoperative. If the head 28 is rotated through 180° so as to bring the inoperative jaw into the operative position the shaft 36 is rotated therewith so that the spring 42 is enabled to actuate the levers 41 and 43 to withdraw the catch 18 thereby freeing the selecting mechanism to change the operating cycle when the machine is started. It is to be observed that the spring 42 is required to overcome the catch spring 22 and consequently has to be stronger than the latter.

Having described our invention, we declare that

what we claim and desire to secure by Letters Patent is:

1. In a typographical composing machine of the kind referred to, the combination of a line transporter, mechanism for raising and lowering the same including a transporter cam and a single cam roller, and selective mechanism for varying the cycle of said transporter so that its jaws are raised and lowered between the line receiving and casting positions only.
2. In a typographical composing machine of the kind referred to, the combination of a line transporter, mechanism for raising and lowering the same including a transporter cam, a single cam roller and a single set of levers, and selective mechanism for varying the cycle of said transporter from that normally employed when matrices are automatically composed by the use of the keyboard in such a manner that the transporter jaws are raised and lowered between the line receiving and casting positions only.
3. In a typographical composing machine of the kind referred to, the combination of a line transporter, mechanism for raising and lowering the same including a transporter cam and a single cam roller, and selective mechanism actuated by manual means for varying the cycle of said transporter so that its jaws are raised and lowered between the line receiving and casting positions only.
4. In a typographical composing machine of the kind referred to, the combination of a line transporter, mechanism for raising and lowering the same including a transporter cam and a single cam roller, and selective mechanism actuated by a member of the machine for varying the cycle of said transporter so that its jaws are raised and lowered between the line receiving and casting positions only.
5. In a typographical composing machine of the kind referred to, the combination of a line transporter, a rotatable head therefor, mechanism for raising and lowering said transporter, and selective mechanism actuated by rotation of said rotatable head for varying the cycle of said transporter so that its jaws are raised and lowered between the line receiving and casting positions only.
6. In a typographical composing machine of the kind referred to, the combination of a line transporter, mechanism for raising and lowering the same including a transporter cam and a single cam roller, said cam being provided with an alternative cam track, and selective mechanism for directing said cam roller on to said alternative track to vary the cycle of said transporter so that its jaws are raised and lowered between the line receiving and casting positions only.
7. In a typographical composing machine of the kind referred to, the combination of a line transporter, mechanism for raising and lowering the same including a transporter cam and a single cam roller, said cam being provided with an alternative cam track which coincides with the normal track for a part of the cam contour and is located below the same for the remainder thereof, and selective mechanism for directing said cam roller on to said alternative track to vary the cycle of said transporter so that its jaws are raised and lowered between the line receiving and casting positions only.
8. In a typographical composing machine of the kind referred to, the combination of a line transporter, mechanism for raising and lowering the same including a transporter cam and a
- 5 single cam roller, said cam being provided with an alternative cam track which coincides with the normal track for a part of the cam contour and is located below the same for the remainder thereof, a movable member forming part of said normal track and connecting the same with said alternative track, and selective mechanism for directing said cam roller on to said alternative track to vary the cycle of said transporter so that its jaws are raised and lowered between the line receiving and casting positions only.
- 10 9. In a typographical composing machine of the kind referred to, the combination of a line transporter, mechanism for raising and lowering the same including a transporter cam and a single cam roller, said cam being provided with an alternative cam track which coincides with the normal track for a part of the cam contour and is located below the same for the remainder thereof, a pivoted finger forming part of said normal track and connecting the same with said alternative track, and an interponent engaging said finger and directing said cam roller on to said alternative track to vary the cycle of said transporter so that its jaws are raised and lowered between the line receiving and casting positions only.
- 15 10. In a typographical composing machine of the kind referred to, the combination of a line transporter, mechanism for raising and lowering the same including a transporter cam and a single cam roller, said cam being provided with an alternative cam track which coincides with the normal track for a part of the cam contour and is located below the same for the remainder thereof, a pair of pivoted fingers forming part of said normal track and joining the same to that part of the cam contour which is common to both tracks, one of said pivoted fingers being provided with a projection, an interponent adapted to engage said projection to move said finger out of the path of said cam roller and permit the same to pass over said alternative cam track to vary the cycle of said transporter so that its jaws are raised and lowered between the line receiving and casting positions only.
- 20 11. In a typographical composing machine of the kind referred to, the combination of a line transporter, mechanism for raising and lowering the same including a transporter cam and a single cam roller, said cam being provided with an alternative cam track which coincides with the normal track for a part of the cam contour and is located below the same for the remainder thereof, a movable member forming part of said normal track and connecting the same with said alternative track, and an interponent directing said cam roller on to said alternative track to vary the cycle of said transporter so that its jaws are raised and lowered between the line receiving and casting positions only, said interponent being brought into operation by means of a spring which is manually released.
- 25 12. In a typographical composing machine of the kind referred to, the combination of a line transporter, mechanism for raising and lowering the same including a transporter cam and a single cam roller, said cam being provided with an alternative cam track which coincides with the normal track for a part of the cam contour and is located below the same for the remainder thereof, a movable member forming part of said normal track and connecting the same with said alternative track, and an interponent directing
- 30
- 35
- 40
- 45
- 50
- 55
- 60
- 65
- 70
- 75

said cam roller on to said alternative track to vary the cycle of said transporter so that its jaws are raised and lowered between the line receiving and casting positions only, said interponent being attached to one end of a spring loaded shaft tending to bring the same into operation, said shaft being provided with a stop engaging a spring loaded pivoted lever which springs into position behind said stop and is removed by manually operated means to enable said spring loaded shaft to actuate said interponent.

13. In a typographical composing machine of the kind referred to, the combination of a line transporter, mechanism for raising and lowering the same including a transporter cam and a single cam roller, and selective mechanism for varying the cycle of said transporter so that its jaws are raised and lowered between the line receiving and casting positions only, said selective mechanism being held out of engagement when the machine clutch is disengaged.

14. In a typographical composing machine of the kind referred to, the combination of a line transporter, mechanism for raising and lowering the same including a transporter cam and a single cam roller, said cam being provided with an alternative cam track which coincides with the normal track for a part of the cam contour and is located below the same for the remainder thereof, a movable member forming part of said normal track and connecting the same with said alternative track, and an interponent directing said cam roller on to said alternative track to vary the cycle of said transporter so that its jaws are raised and lowered between the line receiving and casting positions only, said interponent being attached to one end of a spring loaded shaft tending to bring the same into operation, said shaft being provided with a stop engaging a spring loaded pivoted lever which springs into position behind said stop and is removed by manually operated means to enable said spring loaded shaft to actuate said interponent, and a second pivoted lever connected to the opposite end of the spring loaded shaft to that to which said interponent is attached, the other end of said second pivoted lever engaging the clutch mechanism and arranged to be rocked when the clutch is disengaged so that said first pivoted lever is held behind the stop on said spring loaded shaft.

15. In a typographical composing machine of the kind referred to, the combination of a line transporter, mechanism for raising and lowering the same including a transporter cam and a single cam roller, selective mechanism for varying the cycle of said transporter so that its jaws are raised and lowered between the line receiving and casting positions only, and mechanism operative when the transporter cycle is varied for carrying out a function normally performed by it when it rises to the line distribution position.

16. In a typographical composing machine of the kind referred to, the combination of a line transporter, mechanism for raising and lowering the same including a transporter cam and a single cam roller, selective mechanism for varying the cycle of said transporter so that its jaws are raised and lowered between the line receiving and casting positions only, and mechanism operative when the transporter cycle is varied for releasing the spaceband shifter catch.

17. In a typographical composing machine of the kind referred to, the combination of a line

transporter, a rotatable head for said line transporter provided with a normal and with a detachable jaw, mechanism for raising and lowering said transporter including a transporter cam and a single cam roller, and selective mechanism for varying the cycle of said transporter so that its jaws are raised and lowered between the line receiving and casting positions only.

18. In a typographical composing machine of the kind referred to, the combination of a line transporter, a rotatable head for said line transporter provided with a normal and with a detachable jaw, mechanism for raising and lowering said transporter, including a transporter cam and a single cam roller, an extension on said detachable jaw arranged to engage a push rod which is adapted to release the retaining catch for the spaceband shifter carriage on the jaw ascending to the line receiving position, and selective mechanism for varying the cycle of said transporter so that its jaws are raised and lowered between the line receiving and casting positions only.

19. In a typographical composing machine of the kind referred to, the combination of a line transporter, a rotatable head for said line transporter provided with a normal and with a detachable jaw, mechanism for raising and lowering said transporter, and selective mechanism for varying the cycle of said transporter so that its jaws are raised and lowered between the line receiving and casting positions only, said selective mechanism being brought into operation by rotation of the first elevator head.

20. In a typographical composing machine of the kind referred to, the combination of a line transporter, a rotatable head for said line transporter provided with a normal and with a detachable jaw, mechanism for raising and lowering said transporter including a transporter cam and a single cam roller, the said rotatable head being mounted upon a shaft rotating therewith, said shaft having an eccentric portion which upon rotation actuates connections which release an interponent operating to vary the cycle of the transporter so that its jaws are raised and lowered between the line receiving and casting positions only.

21. In or for a typographical composing machine of the kind referred to, a transporter cam having a double cam track, one track being of normal contour and the other adapted to reciprocate the transporter between the line receiving and casting positions, a portion of the contour of the cam being common to both tracks, and the remainder of the tracks being arranged above one another, movable fingers being provided at either end of the upper track portion joining the two tracks to one another.

22. A transporter cam according to claim 21 wherein the movable fingers are pivoted and spring loaded so that they return to their normal position after movement and wherein the foremost finger is provided with a projection adapted to engage a member to give the same a pivotal movement.

23. In a typographical composing machine of the kind referred to, the combination of a line transporter provided with a head portion adjustable to receive a keyboard-composed line or a hand-composed line as desired, mechanism for raising and lowering the transporter, and selective mechanism for varying the cycle of said transporter so that its head portion is raised and lowered between the line receiving and casting

positions only, said selective mechanism being brought into operation by the adjustment of the head portion to receive a hand-composed line.

24. In or for a typographical composing machine of the kind referred to, a transporter cam having a double cam track, one track being of normal contour and the other adapted to reciprocate the transporter between the line receiving

5 and casting positions, a portion of the contour of the cam being common to both tracks, and the remainder of the tracks being arranged one above another in the same plane.

RICHARD HENRY SCOTT.
WILLIAM FAIRALL GORSE.
ARTHUR STANILAND HAYWARD.
